UNITED STATES PATENT OFFICE.

ROBERT T. REID AND JAMES L. McDONNELL, OF TACOMA, WASHINGTON,
ASSIGNORS OF ONE-HALF TO FRANK C. CARDIN AND JOHN T. BIBB, OF
SAME PLACE.

TELEPHONE SYSTEM.

SPECIFICATION forming part of Letters Patent No. 605,341, dated June 7, 1898.

Application filed September 25, 1897. Serial No. 653,073. (No model.)

To all whom it may concern:

Be it known that we, ROBERT T. REID and JAMES L. McDONNELL, of Tacoma, in the county of Pierce and State of Washington, have invented certain new and useful Improvements in Telephone Systems; and we do hereby declare the following to be a full, clear, and exact description of the invention, such as will enable others skilled in the art to which it appertains to make and use the same.

This invention relates to an improvement in telephone systems, and more particularly to means for calling individual subscribers and permitting them to have the exclusive and undisturbed use of the line, one object of the invention being to provide simple and efficient means for calling any subscriber on a party-line without sounding the signals of other subscribers.

20 A further object is to provide a simple and effectual lock-out device whereby the line can be restricted to the use of any one subscriber to the exclusion of the others.

25 A further object is to provide a telephone system which shall be comparatively simple in construction and arrangement and which shall be effectual in all respects in the performance of its functions.

With these objects in view the invention 30 consists in certain novel features of construction and combinations and arrangements of parts, as hereinafter set forth, and pointed out in the claims.

In the accompanying drawings, Figure 1 is 35 a diagrammatical view. Fig. 2 is a view showing two party-lines connected together at the central office. Fig. 3 is a view illustrating the signal-transmitter and circuits connected therewith. Figs. 4, 5, and 6 are 40 views illustrating the signal-controller. Figs. 7 and 8 are views illustrating switchboard connections. Fig. 9 is a view showing the signal-controllers arranged in series and the signal-bells arranged in local circuits. Fig. 45 10 is a view showing a three-wire system with the signal-controllers arranged in series 45 on one wire, the telephones arranged in parallel between two other wires, and the signal-bells arranged in parallel between one of said 50 wires and the ground. Fig. 11 is a view illus-

trating the telephones and signal-controllers arranged in series.

A B represent the conductors of a party-line, between which the subscribers' telephones and lock-out devices are arranged in 55 parallel, as hereinafter more specifically described.

In Fig. 1 of the drawings the wire A is shown connected with a switch 1, provided with two contact-points 2 3, and the wire B is 60 shown connected with a double-contact key 4. One contact-point 5 of the key is connected, through an annunciator 6 and a battery 7, with the contact-point 2 of the switch 1, and the other contact-point 8 of the key is 65 connected, through an electric generator 9, with the ground. The other contact-point 3 of the switch 1 is connected with a key 11, and the latter is electrically connected with another key 12. The contact-point 13 of the 70 key 11 is connected, through a resistance 14 and a battery 15, with the ground, while the contact-point 16 of key 12 is connected, through said battery alone, with the ground.

A signal-bell C and a signal-controller D are 75 located at each subscriber's station. In constructing the controller D we employ a suitable base 17, on which a frame or standard 18 is located. Electromagnets 19 and 20 are disposed at opposite sides of the frame or standard 18 and supported in horizontal positions in any suitable manner. The coil of the magnet 20 is of low resistance, while the coil of the magnet 19 is of comparatively high resistance, and said magnets are included in 85 series with each other in a multiple-arc circuit between the line conductor A and the ground. A shaft 21 is loosely mounted at the top of standard 18 and carries an escapement-wheel 22, with which escapement-dogs 90 23 24 at the upper end of a lever 25 are adapted to engage and cause the rotation of said escapement-wheel and the shaft 21 when the lever 25 is vibrated. The lever 25 is pivotally supported in the standard 18 at a point below 95 the electromagnet 19 and maintained, by means of a spring 26, normally so disposed that the dog 24 of the pallet will be in engagement with the escapement-wheel and the dog 23 out of engagement with said wheel. An 100

armature 27 for the magnet 19 is secured to the lever 25 at a point above the pivotal support of the latter, so that when the magnet is energized by an intermittent or pulsatory current the lever 25 will be moved in one direction by the magnet and in the other direction by the spring 26, the vibration of said lever resulting, as is obvious, in the rotation of the escapement-wheel and the shaft to which it is secured. A toothed wheel 28 is also secured to the loose shaft 21, and with said toothed wheel contact-arms 29 are adjustably connected by means of pins 30 on said arms. The contact-arms may be adjustably attached to the shaft 21 in some other manner, if desired, without departing from the spirit of our invention. Pins 31 project in diametrically opposite directions from the shaft 21, and the contact-arms 29 of the respective controllers are arranged at different angles to the coöperating pins 31, so that a predetermined extent of rotation of the shaft 21 of each controller will bring a contact-arm 29 in proper position to be engaged by a contact-spring, as presently explained. A lever 32 is pivotally supported in the standard 18 at a point above the pole of the magnet 20, and the movement or play of said lever is limited by means of screws 33 34, located at the respective sides of the lower end thereof. The lever 32 is maintained normally in contact with the stop-screw 33 by means of a spring 35, and to said lever, at a point below its pivotal support, an armature for the magnet 20 is secured. A contact-spring 36 is secured to but insulated from the upper end of the lever 32 and normally disposed slightly out of the path of movement of the contact-arms 29. An arm 37 is secured to move with the lever 32 and is provided at its free end with a hook 38, normally disposed in the path of movement of the stop-pins 31. The contact-spring 36 is connected with the ground, as shown in Fig. 1, and the toothed wheel 28, and consequently the contact-arms 29, are connected, through the electromagnets of the electric bell C, with the line-wire B.

The switch 1, hereinbefore referred to, is normally thrown to the left on contact-point 2. When the switch is in this position, the closing of a subscriber's multiple-arc telephone-circuit by the removal of the hand-phone from the switch-arm will result in the establishment of a circuit from the battery 7 through said switch, the subscriber's telephone-circuit, the key 4, and annunciator 6, thus causing the latter to drop and denote that a subscriber has called.

To call a particular subscriber, the operator will move the switch 1 to the right onto contact-point 3. He will then press the key 12, so as to cause a heavy current from the battery 15 to pass over the wire A, to which the signal-controller magnets are connected. This current will energize the magnets of all the signal-controllers. The magnets 20 of the controllers in attracting their armatures

will cause the arms 37 to move out of the path of the coöperating stop-pin 31. At the same time the magnet 19 will cause a movement of the lever 25 and result in the turning of the shaft 21 (through the medium of the escapement devices, as above explained) to an extent sufficient to move the stop-pin 31 beyond the toothed free end of the arm 37. The operator will now release the key 12 and press the key 11, thus closing the circuit of battery 15 through resistance 14 and causing a light current to pass over the line-wire A and through the magnet-coils of the signal-controllers. The current now flowing through the circuit of the signal-controllers will not energize the core of the low-resistance coarse-wire magnet sufficiently to cause it to move its armature; but said current will result in energizing the fine-wire high-resistance magnet sufficiently to cause it to move its armature and the lever to which said armature is secured. The reason of this is apparent when it is remembered that the strength of an electromagnet is determined by the number of ampere-turns in its coil, and therefore when a weak current flows through a fine-wire coil having a large number of convolutions and a coarse-wire coil having a comparatively small number of convolutions and placed in series with the fine-wire coil the core of the fine-wire magnet will be stronger (on account of the greater number of ampere-turns) than the coarse-wire magnet. The passage of the light electric current over the circuit of the signal-controllers will therefore result in a further rotation of the shaft 21 and the contact-arms 29 carried thereby. By interrupting the light current by means of the key 11 the shaft 21 and contact-arms 29, carried thereby, will be moved step by step, in accordance with the number of times the circuit is made and broken by the key 11, until a contact-arm 29 in the signal-controller of a subscriber whom it is desired to call reaches a position in line with the contact-spring 36 of that controller. The operator will now leave key 11 open and close the key 12, thus short-circuiting the resistance 14 and throwing the full electromotive force of the battery on the circuit of the signal-controllers, thereby causing the magnets 20 to attract their armatures and move the contact-springs 36 toward the contact-arms 29 and causing electrical contact to be made between the contact-spring and contact-arm of the controller in which the contact-arm has been set, as above explained. An open circuit will be thus completed from the magneto-generator 9 at the central office, the key 4, the line-wire B, the signal-bell magnet at the subscriber's station, the contact-arms, the contact-spring 36, and then to the ground. The operator will now close the key 4, so as to cause a pulsatory current to flow on the circuit above traced and result in sounding the bell at the subscriber's station to the exclusion of all the other bells on the party-line. After the sub-

scriber shall have been successfully called the operator will open the key 12, and thus permit the stop-arms 37 of all the signal-controllers to assume their normal positions in 5 the paths of the stop-pins 31 on the shafts 21. He will then operate the key 11 to cause the continued step-by-step rotation of the shaft 21 until the stop-pins 31 of all the signal-controllers reach and are stopped by the respective 10 stop-arms 37, when the contact-arms 29 of the respective controllers will be again in their normal positions.

While the signaling devices may be manipulated by means of the keys and switch at 15 the central office, as above described, we prefer to operate and control said devices in a quicker, more accurate, and surer manner by means of an apparatus located at the central office, which apparatus may be termed a "signal-transmitter."

In constructing our improved signal-transmitter E we employ a suitable box or casing 39, in which a spring-motor 40 is located, said motor being provided with an escapement 41 25 to regulate its operation. A double arm 42 is secured to the shaft 43 of the motor, and concentric with the movement of the free ends of said arm a perforated plate 44 is secured to the frame or casing 39. The shaft 30 43 of the motor also carries a toothed wheel 45, which, with a spring-contact arm 46, constitutes a circuit-breaker. The contact-arm 46 is insulated from the frame of the motor and is connected with one pole of battery 15, 35 the other pole of said battery being grounded, as shown in Fig. 3. A spring-arm 47 bears continuously against the shaft 43 of the motor, so as to electrically connect the make-and-break wheel 45 in circuit with the line-wire 40 A and resistance 14. A lever 49 is pivotally connected at a point between its ends to the frame or casing 39 and provided at one end with a knob 50. The other end of the lever 49 is provided with a tooth 51, which is normally engaged by and forms a stop for the double arm 42. The relation between the toothed end of lever 49 and the double arm 42 is such that when said arm is in engagement with the tooth the free end of the spring-contact arm 46 will be disposed between two 45 of the teeth of wheel 45, and thus the circuit, including said wheel and contact-arm, will be normally open. The stop-lever 49 50 of signal-transmitter E at the central office is connected, through battery 7 and annunciator 6, with the line-wire B. Thus when a subscriber removes his hand-phone from its switch-arm a circuit will be closed, including battery 7, annunciator 6, stop-lever 49, double 55 contact-arm 42, wheel 45, and the line-wires A and B, and result in causing the drop of the annunciator. One end of the coil of an electromagnet 52 is electrically connected with the perforated plate 44, and the other 60 end of said coil is connected with the line-wire A. The armature-lever 53 of the magnet 52 is maintained normally in contact with

a stop-screw 54 by means of a spring 55 above said lever, and the stop-screw 56 under said lever is electrically connected with the magneto-generator 9. The armature-lever 53 is electrically connected with the line-wire B. A spring-contact arm 57 is located between one end of the perforated plate 44 and the toothed end of the lever 49, said contact-arm 70 57 being in the path of movement of the double arm 42 and electrically connected with the line-wire A. The perforations of the plate 44 are numbered consecutively to correspond with the calls of the various subscribers on 80 a party-line, and in one or another of said holes a pin 58 is placed, so as to be in the path of movement of the ends of the double arm 42 and stop said double arm and the make-and-break wheel 45 when the step-by-step 85 devices of the controllers shall have operated to place the controller of the desired subscriber in proper position for calling.

When it is desired to call a subscriber on a party-line, the operator will first insert the 90 pin 58 in the proper hole or socket in the plate 44 and then move the lever 49, so as to release the double arm 42 and the spring-motor. The double arm 42 and wheel 45 will then commence to move a tooth of the wheel 95 45, riding under and in contact with the contact-arm 46 and one end of the double arm 42, simultaneously engaging the contact-arm 57. Thus as the arm 42 and wheel 45 move a heavy current from battery 15 will flow 100 over the circuit in which the signal-controllers are included and cause the magnet 20 to operate to release the stop-arms 37 from the stop-pins 31, as hereinbefore explained. The circuit just described can be traced from 105 the battery 15 to contact-arm 46, through wheel 45 to double arm 42, to contact-arm 57, to line, and through controller-magnets to ground. As the double arm 42 and wheel 45 continue their movements the former will 110 ride past the contact-arm 57 and another tooth of the wheel will ride under the contact-arm 46. The arm 42 having broken contact with the arm 57, the resistance 14 will be no longer short-circuited, but will now be included in 115 a circuit with the wire A, (with which the signal-controllers are connected,) the wheel 45, contact-arm 46, and battery 15. Thus as the wheel 45 continues to rotate its teeth will pass under and make electrical contact 120 with the arm 46, so as to make and break the circuit of the signal-controllers, and thus cause a pulsatory current to flow over said circuit to effect the step-by-step movement of the signal-controllers until the double arm 125 42 engages the pin 58, when the contact-arm in the controller of the subscriber to be called is in the proper position. The contact of the arm 42 with the pin 58 places the electromagnet 52 (which is of comparatively low 130 resistance) in a shunt-circuit around the resistance 14 and thus causes a heavy current to flow over the circuit of the signal-controllers, whereby to cause the magnet 20 to

- move the lever 32 and bring the contact-spring 36 into contact with the contact-arm 29 of the controller at the subscriber's station to be called. The contact of the arm 42 of the transmitter with the pin 58 also causes the magnet 52 to be energized and operate the armature-lever, so as to close the circuit of the magneto-generator to the line B and through the signal-bell, as before explained.
- 10 The subscriber having been called, the operator will remove the pin 58 and thus permit the operation of the spring-motor to bring the arm 42 again into engagement with the stop-lever 49 and the controller-circuit to be made and broken to bring the controllers to their normal positions, as hereinbefore explained.

In the form of the invention shown in Fig. 9 the magnets of the several controllers on the line are arranged in series, while the signal-magnets of the various subscribers are each arranged in local circuits, including suitable batteries and the contact-arms of the controllers.

25 In the arrangement shown in Fig. 10 three line-wires are employed. The telephones are arranged in parallel between two of said wires, the magnets of the controllers are arranged in series on another wire, and the signal-bells are arranged in parallel between one of the telephone-wires and the ground. In other respects the arrangement shown in Fig. 10 is substantially as hereinbefore explained.

35 It is obvious that the construction of the signal-transmitter at the central office can be modified slightly to operate with the arrangements of circuits and devices shown in Figs. 9 and 10.

40 In Fig. 11 several telephones 60 are shown arranged in series with several signal-controllers 61. Condensers 62 are placed in shunts around the coils of the magnets of the signal-controllers to reduce the self-induction on the circuit, so that the telephones will work satisfactorily. In this figure only the transmitters of the telephones and the coils of the controller-magnets are shown.

In Fig. 7 is shown the connections of a switch-cord at the central office. The signal-transmitter is shown at E. A double-throw double-pole switch is shown at 63. The operator's telephone is shown at 64 and the listening-key at 65, by means of which latter the operator's telephone may be put into circuit. At 66 and 67 double conductor plugs or wedges are shown attached to cords. These plugs or wedges always connect in the spring-jacks, so that wires A' and A² always connect with the controller-wires A, and B' and B² with the bell-wires B. When a subscriber calls, the operator inserts plug 67 in the proper spring-jack, presses down the listening-key, and learns the number required, at the same time throwing the switch 63 to the left, cutting in his transmitter. He then inserts plug 66 in the spring-jack of the line

required and operates his signal-transmitter, as above explained, to ring the proper bell, after which he throws the switch 63 to the right, connecting the lines, so that two subscribers can converse. At 68 a "ring-off" annunciator is shown, and at 69 a battery is illustrated for operating the same. The self-induction of the annunciator prevents the talking-circuit from being short-circuited or crossed through it and the battery. It is evident that in place of the switch 63 and the listening-key a special combination-switch might be used which would perform the function of both.

In Fig. 8 is shown the central-office arrangement of a party-line. A and B are the controller and bell wires, and 69 the annunciator, and 70 the battery for the annunciator. A spring-jack is shown at 71 and is of such construction that when a wedge or plug is inserted into it the annunciator and the battery will be disconnected from the wires A and B and the latter connected to the ring-off annunciator and the battery, as above explained.

In order to provide a simple and efficient means whereby to lock out all subscribers but the one having use of the line, so that when one subscriber is using the line others cannot interrupt or hear his conversation, the devices now to be described will be employed.

F, Fig. 1, represents the hanger or switch-arm of the subscriber's telephone and is pivotally supported at or near its center, one end of said hanger or arm being made with a hook 72 and the other end being beveled, as at 73. An electromagnet is shown at 74 and provided with a polarized armature 75, pivotally supported at 76. An arm 77 projects from the center of the armature at right angles thereto, said arm being provided at its free end with a beveled tooth 78, normally disposed under the beveled end of the switch-arm F. The arm 77 plays between stops 79 and 80 and is held normally against the stop 79 by means of a spring 81. A current of one polarity passing through the coils of magnet 74 will cause the arm 77 to move to the right against the pull of spring 81, while a current of the opposite polarity will cause it to remain against the stop 79. The weight of the hand-phone on the hooked end of the switch-arm F or hanger F maintains the latter normally out of contact with the contact-screw 82, which forms a part of the local telephone-circuit. When the hand-phone is removed from the hooked end of the hanger or switch-arm F, the spring 83 will cause said hooked end of the hanger or switch-arm to rise toward the contact-screw 82 and the beveled end to descend and make contact with the tooth 78 at the upper end of the arm 77. This completes the circuit of the line-wires A and B through the switch-arm or hanger F, arm 77, electromagnet 74, annunciator 6, and battery 7. If the current is of the right polarity, the arm

77 will move from under the beveled end of the switch-arm or hanger F, allowing the hooked end thereof to rise and make contact with the contact-screw 82, cutting in the subscriber's telephone and breaking the circuit through the electromagnet 74, which will also allow the spring 81 to return the arm 77 to its normal position against the stop 79. The tooth 78 at the upper end of the arm 77 will now be disposed above the beveled end of the switch-arm or hanger, which has descended. When the hand-phone is again hung up, the beveled end of the switch-arm or hanger F will ride past the tooth 78 of arm 77, pushing it away momentarily, and said switch-arm or hanger will assume its normal position out of contact with the contact-screw 82, thus breaking the circuit through the subscriber's telephone.

20 Should a current of the opposite polarity pass through the coils of the magnet 74 when the hand-phone is removed and the beveled end of the switch-arm or hanger F makes contact with the tooth 78 of arm 77, the latter will remain against the stop 79, keeping the tooth 78 in the path of the beveled end of the switch-arm or hanger F, so that the hooked end of the latter cannot rise and make contact with the contact-screw 82, thus keeping the subscriber's telephone locked out. The battery 7, which is kept on the line when it is not in use, has its poles so connected that when a subscriber takes down his hand-phone the current through his lock-out magnet 74 (when the beveled end of the switch-arm or hanger makes contact with the tooth 78 of arm 77) will be in the proper direction to cause the movement of tooth 78 of arm 77 out of the path of the beveled end of the switch-arm or hanger, thus allowing the subscriber to cut in his telephone and drop the annunciator 6. The ring-off battery (shown in Figs. 7 and 8) is connected oppositely from the battery 7, so that while it is in use if a subscriber should take down his hand-phone the direction of the current through his lock-out magnet 74 will be such that the tooth 78 of arm 77 will remain in the path of the beveled end of the switch-arm or hanger and keep his telephone cut out.

In Fig. 2 are theoretically shown two party-lines (G-H and G'-H') connected together at the central office. In Fig. 1 wire A is connected with the positive poles of battery 7 and wire B to the negative poles thereof. In Fig. 2 wires G and G' (corresponding to the wires A of two lines) are connected to the negative plate of the battery, and the wires H H' (corresponding to the wires B of two lines) are connected to the positive pole of said battery.

Our improvements are comparatively simple in construction, easy to manipulate, and effectual in all respects in the performance of their functions.

Various slight changes other than those above enumerated may be resorted to with-

out departing from the spirit of our invention or limiting its scope, and hence we do not wish to limit ourselves to the precise details herein set forth.

Having fully described our invention, what we claim as new, and desire to secure by Letters Patent, is—

1. In a telephone system, the combination with a party-line and subscriber's signal, of a controller for each signal, each controller having a normally open circuit-closer for controlling the circuit of the subscriber's signal, a step-by-step device for each circuit-closer, having a part adapted to move always in the same direction, an electromagnet of high resistance for operating said step-by-step device, a stop device adapted to arrest the circuit-closer of each controller, a magnet of low resistance in series with the high-resistance magnet for controlling said stop device and devices at the central office for controlling current through the coils of said magnets whereby to cause one signal-controller at a time to close the circuit of the co-operating subscriber's signal, substantially as set forth.

2. In a telephone system, the combination with a party-line and subscribers' signals, of a controller for each signal, each controller comprising a circuit-closer in a normally open circuit for controlling the co-operating signal, stop devices, step-by-step devices having a part to move always in the same direction, an electromagnet for operating the circuit-closer and step-by-step devices, an electromagnet of lower resistance than the first-mentioned one for operating the stop devices to release the circuit-closer, said magnets being included in series with each other in a multiple-arc circuit and means at the central office for causing currents of different electro-motive force to flow over the circuit of said electromagnets, substantially as set forth.

3. In a telephone system, the combination with a party-line and subscribers' signals, of a controller for each signal, each controller comprising a circuit-closer for controlling the circuit of the co-operating subscriber's signal, a step-by-step device for operating said circuit-closer, an electromagnet for operating said circuit-closer, a stop device for the circuit-closer, an electromagnet for operating said stop device and of lower resistance than the first-mentioned magnet, coils of said magnets being arranged in series, a generator at the central office, a resistance at the central office and devices at the central office for including said resistance in the circuit of said magnets and battery at one time and for excluding said resistance from said circuit at another time, substantially as set forth.

4. In a telephone system, the combination with two conductors of a party-line and telephones included in parallel between said conductors, of a signal-controller at each subscriber's station, each controller comprising a normally open circuit-closer, step-by-step devices for operating said circuit-closer, high-

resistance electromagnetic devices for operating said step-by-step devices, stop devices for the circuit-closer and low-resistance electromagnetic devices for controlling said stop devices and included in series with the high-resistance electromagnetic devices, a signal in a multiple-arc circuit from one of the line conductors to the ground and including said circuit-closer, devices at the central office for causing currents of different electromotive force to flow over the circuit of said electromagnetic devices, and means for causing a pulsatory current to pass over the circuit of the multiple-arc circuit including the subscriber's signal and circuit-closer, substantially as set forth.

5. In a telephone system, the combination with a party-line and subscribers' signals, of a controller for each signal, each controller comprising a circuit-closer, a step-by-step device for operating said circuit-closer, a lock device for the circuit-closer, electromagnets for the step-by-step devices and the lock devices respectively, a signal-transmitter at the central office comprising a make-and-break wheel, an arm carried thereby, a contact-arm to engage the make-and-break wheel, a lock-lever for the arm carried by the make-and-break wheel, means for stopping said arm and the make-and-break wheel at the desired point, a normally open circuit including one line-wire, the make-and-break wheel, the contact-arm which co-operates therewith, a resistance and a battery, a contact-arm connected with said line-wire and adapted to be engaged by said first-mentioned arm whereby to short-circuit the resistance and a normally closed circuit including both line-wires, a battery, an annunciator, the lock-lever, the first-mentioned arm the make-and-break wheel and the resistance, substantially as set forth.

6. In a telephone system, the combination with a party-line and subscribers' signals, of a controller for each signal each controller comprising a step-by-step circuit-closer, a lock device, an electromagnet of high resistance to operate the step-by-step circuit-closer, an electromagnet of low resistance to operate the lock and complete the circuit through the circuit-closer and signal, a transmitter at the central office for operating said signal-controllers, said transmitter comprising a motor, a make-and-break wheel and a double arm

carried by the shaft of said motor, a contact-arm co-operating with said make-and-break wheel, said contact-arm and make-and-break wheel being included in a normally open circuit with a battery, a resistance and one of the line-wires, a locking-lever for the double arm, a contact-arm connected with said line-wire and co-operating with the double arm to short-circuit said resistance, a plate having a series of sockets or perforations, a metallic pin to enter one or another of said sockets or perforations whereby to stop the double arm and make-and-break wheel, an electromagnet included in circuit with said plate and said line-wire and an armature-lever for said magnet included in a normally open circuit with the other line-wire and a magneto-generator, substantially as set forth.

7. In a telephone system, the combination with the conductors of a party-line, of a series of telephones arranged in parallel between said conductors, a switch-arm for each multiple-arc telephone-circuit, an electromagnet, a polarized armature for said magnet, an arm on said armature normally disposed under one end of said switch-arm, and a circuit in parallel with the telephone-circuit and including said electromagnet, the arm on the armature thereof and said switch-arm, substantially as set forth.

8. In a telephone system, the combination with the conductors of a party-line, of a series of telephones arranged in normally open circuits in parallel between the line conductors, a switch-arm or hanger forming part of each telephone-circuit and beveled at one end, an electromagnet, a polarized armature therefor, an arm projecting from said armature and having a tooth at its free end normally disposed under the beveled end of the switch-arm or hanger and a circuit in parallel with the telephone-circuit and including said electromagnet, the arm on the armature thereof, the switch-arm or hanger and said line conductors, substantially as set forth.

In testimony whereof we have signed this specification in the presence of two subscribing witnesses.

ROBERT T. REID.
JAMES L. McDONNELL.
